UNITED STATES PATENT OFFICE.

ALFRED A. CRIMP, OF CHICAGO, ILLINOIS.

SOCKET WRENCH.

Application filed May 25, 1922. Serial No. 563,492.

To all whom it may concern:

Be it known that I, ALFRED A. CRIMP, a citizen of the United States, residing at Chicago, in the county of Cook and State of Illinois, have invented certain new and useful Improvements in Socket Wrenches, of which the following is a description.

My invention relates to improvements in socket wrenches and more particularly to a unitary socket wrench capable of operating on nuts or bolt heads or the like of varying sizes.

The invention has among its objects the production of a device of the kind described which will be simple, convenient, compact, neat and attractive in appearance, durable, reliable, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is an elevation of my device;

Fig. 2 is a top plan view thereof;

Fig. 3 is an enlarged section taken substantially on the line 3—3 of Fig. 2;

Fig. 4 is a fragmentary section similar to that shown in Fig. 2, illustrating the device in operation;

Fig. 5 is a section substantially on the line 5—5 of Fig. 3;

Fig. 6 is a section substantially on the line 6—6 of Fig. 3;

Fig. 7 is a section substantially on the line 7—7 of Fig. 3;

Fig. 8 is a side elevation of one of the series of sockets;

Fig. 9 is a side elevation of another of said sockets;

Fig. 10 is an end view of the socket shown in Fig. 9;

Fig. 11 is a fragmentary section showing the manner of securing the springs to the sockets;

Fig. 12 is a longitudinal section of a modified form of wrench;

Fig. 13 is a section taken substantially on the line 13—13 of Fig. 12; and

Fig. 14 is a fragmentary section showing the wrench in use.

In the drawings, wherein I have illustrated the preferred embodiments of my invention, 1 indicates an outer socket or casing of a suitable shape to receive a nut or the like. A stem 2 is secured to the casing by any suitable means, as, for instance, by welding, screw threading or the like, said stem preferably having a plurality of annular shoulders or steps 3 therein at its inner end. Slidable within the casing 1 is a series of nested sockets 4, 5 and 6, of progressively decreasing size to accommodate nuts or bolt heads of various sizes and shape. Each of the sockets 4, 5 and 6 has one or more slots 8, 9 and 10 respectively, through the side wall thereof, said slots extending longitudinally of the parts. Projecting inwardly from the casing 1 is one or more pins 11 slidable in the slots 8 and 9, and the center socket 5 has one or more pins 12 projecting inwardly to slidably engage in the slot 10 of the socket 6.

By means of the pin and slot arrangement the parts further are limited in their movement outwardly of the casing, aligning the outer ends of the sockets, as shown in Fig. 3.

Preferably secured to the inner ends of the sockets 5 and 6 by welding, brazing or the like, are one or more lugs or projections 13 having openings or apertures therethrough to receive the ends of coil springs, as shown. The coil springs 14, 15 and 16 are provided, one for each of the sockets 4, 5 and 6, and arranged between said sockets and the stem 2. The outer spring engages the outer shoulder formed by the casing and stem, the inner end fitting into the space between the casing 1 and the socket 5 and bearing on the inner end of the socket 4 to yieldably press it outwardly of the casing. The springs are of progressively decreasing diameter, and concentrically arranged and may be of progressively varying strengths or tensions decreasing from the largest to the smallest. In this way it will require a greater thrust to compress one spring a

given distance than the next weaker spring. The spring 15 engages at one end in the intermediate shoulder of the stem, while the spring 16 engages the stem at the inner shoulder. The outer ends of the springs 15 and 16 may be slidably inserted through the apertures formed in the lugs 13 at the ends of the sockets 5 and 6 to prevent their getting out of position.

10 In operation, the unitary device is placed above the nut 17 to be turned and pressed down, whereat the socket member smaller than the nut will be pressed inwardly against the spring pressure while the next 15 larger or proper sized socket member will engage said nut, as shown in Fig. 4. It will be noted that whenever the socket 5 is moved inwardly, the pin 12 will cause the socket 6 to be moved together with the 20 socket 5.

In case that a nut of a size to fit the socket 5, for example, is to be engaged, then upon applying the wrench, only the socket 6 will be moved inwardly to its inoperative 25 position. It is to be especially noted that all of the sockets are open at their inner ends so that the bolt or any other projecting part adjacent the nut may extend into the casing for its full length and without 30 obstruction or interference of any sort therewithin.

In the modification shown in Figs. 12-14 the sockets 4, 5 and 6 have webs 18, 19 and a 20 respectively at their inner ends and a 35 web 21 is arranged at the inner end of the casing 1. The springs, 14, 15 and 16 preferably of decreasing tensions are arranged substantially as previously described except that they do not surround one another and 40 bear at both ends against the web members.

The socket members 4, 5 and 6 are slotted as before and a pin 22 is arranged diametrically through said slots and casing.

In the claims it is to be understood that 45 the term "nut" includes any type of nut or bolt head or similar structure.

Having thus described my invention, it is obvious that various immaterial modifications may be made in the same without 50 departing from the spirit of my invention; hence I do not wish to be understood as limiting myself to the exact form, construction, arrangement and combination of parts herein shown and described or uses mentioned.

What I claim as new and desire to secure by Letters Patent is:

1. A wrench comprising a stem, a socket casing, a series of sockets slidably nested in said casing, and means between said parts 60 for permitting said sockets to move automatically to accommodate various sized nuts, said means comprising coil springs each having one end engageable with said stem and the other end secured to one of 65 said sockets, and pins secured to alternate sockets and casing and slidable in slots in said sockets to limit the relative longitudinal movement and align the outer ends of said sockets. 70

2. A wrench comprising a stem, a socket casing, a series of sockets slidably nested therein, and means between said parts for permitting said sockets to move automatically to accommodate various sized nuts, 75 said means comprising apertured lugs secured to the inner ends of said sockets, coil springs having one end engageable with said stem and the other end insertable 80 through said lugs, and pins secured to alternate sockets and casing and slidable in slots in said sockets to limit the relative longitudinal movement and align the outer ends of said sockets. 85

3. A wrench comprising a stem, a socket casing having a series of annular stepped shoulders, a series of sockets slidably nested in said casing, each having an elongated slot through its side wall and means between said parts for permitting said sockets 90 to move automatically to accommodate various sized nuts, said means comprising apertured lugs secured to the inner ends of said sockets, coil springs of progressively varying 95 diameters in said casing, each having one end engageable with one of said shoulders of the same, and the other end bearing on the inner end of one of the sockets and insertable through the lug thereon and pins secured to alternate sockets and casing and 100 slidable in said slots to limit the relative longitudinal movement and align the outer ends of said sockets. 105

In testimony whereof I have hereunto signed my name in the presence of two subscribing witnesses

ALFRED A. CRIMP.
